UNITED STATES PATENT OFFICE

148,804

DESIGN FOR AN EGG CONTAINER

Florence K. Lewis and Evelyn Trout,
Glendale, Calif.

Application April 27, 1946, Serial No. 129,013

Term of patent 3½ years

(Cl. D58—13)

To all whom it may concern:

Be it known that we, Florence K. Lewis and Evelyn Trout, citizens of the United States, both residing in Glendale, in the county of Los Angeles and State of California, have invented a new, original, and ornamental Design for an Egg Container, of which the following is a specification, reference being had to the accompanying drawings, forming a part thereof.

Figure 1 is a top plan view of an egg container showing our new design.

Figure 2 is a side elevation.

Figure 3 is an end elevation.

Figure 4 is a bottom view.

We claim:

The ornamental design for an egg container, substantially as shown.

FLORENCE K. LEWIS.
EVELYN TROUT.
